Primary Examiner — Katrina A Betton

(57) **CLAIM**

The ornamental design for a vehicle interior as shown and described.

DESCRIPTION

The patent or application file contains at least one drawing executed in color. Copies of this patent or patent application publication with color drawing(s) will be provided by the Office upon request and payment of the necessary fee.

1. Vehicle interior

1.1 : Perspective

1.2 : Perspective

1.3 : Front

1.4 : Back

1.5 : Left

1.6 : Right

1.7 : Top

1.8 : Bottom

Novelty is claimed in the features of shape and configuration of the vehicle interior shown in the accompanying drawings; the color is not to be claimed; the characteristic features of the design lie in the shape; the parts marked with red layers do not form part of the claimed design; Fig. 1.1 is a front, right and top side perspective view of a vehicle interior showing our new design; Fig. 1.2 is a rear, right and top side perspective view thereof; Fig. 1.3 is a front elevation view thereof; Fig. 1.4 is a rear elevation view thereof; Fig. 1.5 is a left side elevation view thereof; Fig. 1.6 is a right side elevation view thereof; Fig. 1.7 is a top plan view thereof; and Fig. 1.8 is a bottom plan view thereof.
